(57) **CLAIM**

I claim the ornamental design for a mop wringer, as shown and described.

DESCRIPTION

FIG. 1 is an upper perspective view from a first side showing my new design for a mop wringer;

FIG. 2 is an upper perspective view from a second side showing the design of FIG. 1;

FIG. 3 is a front view showing the design of FIG. 1;

FIG. 4 is a rear view showing the design of FIG. 1;

FIG. 5 is a top view showing the design of FIG. 1;

FIG. 6 is a bottom view showing the design of FIG. 1;

FIG. 7 is a first side view showing the design of FIG. 1;

FIG. 8 is a second side view showing the design of FIG. 1;

FIG. 9 is an enlarged partial front view showing a detail of FIGS. 3; and,

FIG. 10 is an enlarged partial front view showing a detail of FIG. 1.

In FIGS. 1-10, the broken lines are for purposes of illustration only, and do not form a part of the claimed design.
